Patented July 25, 1961

190,953

COMBINED TRAILER AND CABLE PULLER

Gerald A. M. Petersen, Santa Clara, and Robert W. Goode, Morgan Hill, Calif.; said Goode assignor to said Petersen

Filed Feb. 6, 1959, Ser. No. 54,501

Term of patent 14 years

(Cl. D14—3)

Des. 190,953

PAGE 2

FIG. 2

FIG. 3

FIG. 4

FIG. 1 is a perspective view of the combined trailer and cable puller embodying our new design therefor.

FIG. 2 is a plan view of the combined trailer and cable puller shown in FIG. 1.

FIG. 3 is an elevational view of the side shown in FIG. 1.

FIG. 4 is an elevational view of the side opposite to that shown in FIG. 1.

We claim:

The ornamental design for a combined trailer and cable puller, as shown.
